UNITED STATES PATENT OFFICE.

HENRY DAVENPORT AND GEORGE DAVENPORT, OF SOMERVILLE, PA.

MAGIC LANTERN.

SPECIFICATION forming part of Letters Patent No. 320,636, dated June 23, 1885.

Application filed March 6, 1885. (No model.)

To all whom it may concern:

Be it known that we, HENRY DAVENPORT and GEORGE DAVENPORT, both of Somerville, in the county of Philadelphia and State of Pennsylvania, have invented a new and Improved Reflecticon, of which the following is a full, clear, and exact description.

The object of our invention is to provide a new and improved apparatus for reflecting pictures, &c., on a screen or white wall.

The invention consists in the combination, with a box having a mirror on the inner surface of each end, and two mirrors on the inner surface of the front, of a lens-tube in the front and a picture-holding slide on the back.

The invention also consists in various parts and details and combinations of the same, as will be fully set forth hereinafter.

Reference is to be had to the accompanying drawings, forming part of this specification, in which similar letters of reference indicate corresponding parts in all the figures.

Figure 1 is a rear view of our improved reflection. Fig. 2 is a longitudinal sectional elevation of the same on the line *yy*, Fig. 3. Fig. 3 is a cross-sectional elevation of the same on line *xx* in Fig. 1. Fig. 4 is a plan view of the same.

On the inner surface of each end *B* of a box, *A*, a concave reflector or mirror, *C*, is secured, and on the inner surface of the front *D* a concave mirror or reflector, *E*, is secured at each end in such positions as to concentrate the light upon the picture at *N*. Between the mirrors *E* a tube, *F*, projects inward from the front *D*, and in the same a sliding tube, *G*, is arranged, holding a double convex lens, *H*.

A rod, *J*, extends from the inner tube, *G*, up to the top of the back *K* of the box, and is used for focusing the lens-tube *G*. In the box *A* two lamps, *L*, or other lights—such as calcium-lights, electric lights, &c.—are placed between the mirrors *C E* at each end.

A detachable funnel, *M'*, is arranged above each light on the top *V* of the box, which top has a curved under side which is silvered and polished or made bright in any other suitable manner to reflect the rays of light. A ventilating-opening, *V'*, is arranged in the said top, and is provided with a hood, *V''*, which ventilating-opening permits the hot air to escape. The front corners of the box are rounded. A

circular aperture, *N*, is provided in the middle of the back *K*, and two longitudinal grooves or cleats, *L'*, are secured on the outer surface of the back of the box. Between them a sliding apparatus, *O*, is arranged, having two apertures, *P*, which can be closed by hinged doors *Q*, which can be held closed by pivoted buttons *R*.

A door, *S*, is hinged on the front of the box below or at either side of the tube *F*, and on the inner side of the said door a flat mirror or reflector, *T*, is secured. The box has a perforated bottom, *U*, to admit air.

The pictures *W* are placed in the sliding piece *O*, and held in place by closing the doors *Q*, and then one picture is shifted to appear in the opening *N*. The light from the two lamps is reflected by the mirrors *C E* upon the picture, and from the same through the lens *H* upon a screen or wall. By means of the mirror *T* it can be reflected upon a wall at either side of the box or upon the ceiling.

The reflection of the picture on the wall or screen can be enlarged more or less by moving the reflecticon to or from the screen or wall. The pictures never become heated sufficiently to injure them, and may remain in the apparatus for hours without being destroyed. Any opaque object—such as a photograph, chromo, drawing, &c.—can easily be reflected upon the screen in any desired size, and all parts will be clear and distinct, so as to be seen clearly and distinctly by a large audience.

Having thus described our invention, what we claim as new, and desire to secure by Letters Patent, is—

1. The combination, with the box *A*, of the mirrors *C E*, the lens-tube *F*, the sliding tube *G*, the lens *H* in the same, and the rod *J*, substantially as herein shown and described.

2. The combination, with the box *A*, of the mirrors *C E*, the tube *F*, the sliding tube *G*, the lens *H*, and the rod *J*, extending from the tube *G* to the top of the back of the box, substantially as herein shown and described.

HENRY DAVENPORT.
GEORGE DAVENPORT.
